ABSTRACT OF THE DISCLOSURE

An apparatus for continuous crust breaking and oxide charging of a furnace including a travelling gantry framework spanning the furnace for supporting the operating means with limit switches on said framework for automatically terminating the operations at the ends of the furnace. Auxiliary wheel means are provided for raising the framework free of the floor and transversely shifting the unit to new position and a rotatable power boom is included to allow power to be taken from overhead rails along either side of the furnace.

This application is a continuation-in-part of an application entitled, "Means for Operating Aluminum Electrolysis Furnaces, Including Crust Breaking and Oxide Charging," Ser. No. 348,521, filed Mar. 2, 1964, now abandoned.

The present invention relates to electrolytic cells or furnaces and, more particularly to apparatus for automatic feeding of the cells.

In the operation of aluminum electrolysis furnaces, it has become conventional, for the breaking of furnace crusts and the charging of oxide and other materials required for the running of the furnace, to use automated mechanical equipment in lieu of the prior manual operations of breaking the crust by sledge and/or crowbar and charging by spade and hand car. In this manner, it has been possible to advantageously reduce the need of manpower, since a single man may operate the entire equipment, both for the crust breaking and the oxide charging and any other necessary operation. However, such mechanical equipment is quite heavy so that it has been found to be necessary to mount the same in special cars or travelling crabs that move along the furnace. Also, it has been found that a necessary requirement is to provide for protection of the operator of such equipment, both against the heat from the furnaces and against escaping gases.

Thus, one object of the present invention is to provide means which to an even higher degree than before reduces the need of manual labor and greatly simplifies the equipment and the supporting structure.

It is another object of the present invention to eliminate the need for complicated and expensive safety devices to protect the operator since the entire operating means of the present invention may be operated from a remote point in the building, at a good distance from the furnaces themselves.

In accordance with the invention, there is provided a gantry or portal-like framework which is movable longitudinally along the furnace or furnaces and which, on at least one transverse side thereof, carries an oxide charging silo and a crust breaking device. One important and characteristic feature of the apparatus of the invention is the provision of electric contact means adapted to cooperate

with stationary stops at the ends of the individual furnaces for operating a master control circuit which, in turn, automatically controls the movements of the gantry framework, the operation of the crust breaking device and the outlet valve of the oxide charging silo. In addition, auxiliary wheels are provided on the framework for shifting the furnace operating means from one furnace to another in response to the master control circuit and along a path transverse to the furnaces themselves. As a result, when the apparatus of the present invention is utilized, the operator does not have to accompany the equipment during the operation on each individual furnace or during the shifting operation from one furnace to the other. Furthermore, the gantry framework provides the operating means with improved stability so that the heavy equipment is always assuming a correct position relative to the furnace being treated. It is also an advantage of the gantry framework of the present invention that the equipment, which is not only very heavy, but also subjected to intensive dynamic and/or sidewise strains under operation, is rigidly mounted along the depending legs of the framework so as to be supported near to the floor of the building.

The importance of the auxiliary wheels for moving the entire furnace operating equipment from one furnace to the next lies in the fact that this reduces the number of units in a particular building to a minimum. Specifically, in accordance with this feature, the framework is provided with auxiliary wheels adapted to be raised and lowered into and out of engagement with the floor and having a direction of movement transverse to the longitudinal direction of the furnaces. The arrangement is such that the ordinary travelling wheels for the movement of the framework along the furnace during the feeding operation are raised clear of their respective rails when the auxiliary wheels are in operative position against the floor.

To provide power to the individual driving motors for the wheels of the framework and the operation of the crust breaking and oxide charging equipment, the gantry framework may be provided with a selectively rotatable trolley or boom carrying contact pieces adapted to cooperate with contact rails extending longitudinally along the furnace or furnaces. In this manner, no cable conductors to the equipment are needed, so that the floor remains free of these obstructions and the possibility of damage to the cables is avoided, which has been a problem in the past.

In the drawings:

FIGURE 1 shows an operating unit constructed in accordance with the present invention as seen longitudinally of an electrolysis furnace; all parts which are not essential to the understanding of the invention, such as the crust breaking equipment and the furnace proper, being in part deleted and in part shown strictly schematically;

FIGURE 1a is a view taken along line 1a—1a of FIGURE 1; and

FIGURE 2 is a schematic diagram of the control system for the operating unit of FIGURE 1 showing the manner in which the several parts and elements are interrelated in accordance with the invention.

As shown in FIGURE 1 of the drawings, the operating unit comprises a lattice framework 1 mounted on a suitable number of bogies 2, each provided with a wheel 2a and a gear motor 3 for driving at least one of said wheels 2a for effecting movement of the unit along furnace or cell F and from one operating location to another as required. The motors 3 are reversible so that the unit may be run in either direction along the furnace F. In the upper part of the preferred embodiment of the unit, each leg L is provided with an oxide silo 4 having a filling opening 4a for charging the furnace F in a manner to be discussed later. The framework 1 also carries a power transfer arm 5 which is pivotable about the vertical axis

by a turntable 6 and also pivotable about a horizontal axis at a pivot pin 7. The turning in the horizontal plane may be effected by means of a motor 8 connected to the turntable 6, while the vertical positioning about the pin 7 is effected under the control of a hydraulic cylinder 9. Electric current collectors 11 are arranged at the free end of the arm 5 so as to be adapted to cooperate with power rails 12 extending along the furnace F; the power rails 12 being suspended from a wall W of the building, if desired.

The crust breaker does not constitute any part of the present invention, and is thereby merely schematically indicated at 10 at the lower part of the legs L of the framework 1. As is conventional, tools 10a extend downwardly into engagement with or in juxtaposition to the crust on the surface of the molten metal in the furnace F for performing the usual crust breaking function.

At the lower end of the charging silos 4, there is provided a conventional electrically operated valve 13 from which two tubes 14, 14a (see FIGURE 1a) are extending downwardly towards the furnace so as to deliver charging oxide to the furnace F. The tubes 14 open just adjacent to opposite sides of the crust breaking tool 10a; only one such tube 14, 14a being in operation at a time, that is the one which has its outlet opening behind the crust breaking tool in the direction of movement of the unit. The arrangement allows the oxide from the operative tube 14, 14a to be always caused to flow into the opening in the furnace crust provided by the tool 10a that precedes it along the furnace F.

A transversely running wheel 15 is arranged in connection with each bogie 2 (the near two being viewable in FIGURE 1); such wheels 15 being mounted on pivotal levers 15a so as to be adapted to be positioned in the raised position during usual operation along the furnace F, as shown, but adapted to be lowered by means of a hydraulic cylinder 16 to thereby raise the entire framework 1 whereby the ordinary running wheels 2a in the bogies 2 are cleared from their rails and the framework may be shifted transversely of the furnace F to a new furnace F', for example.

The framework 1 carries limit contact switches 18, 19 adapted to cooperate with fixed sensor arms of stoppers 18a, 19a mounted on opposite ends of the furnace F; as shown in FIGURE 1, for a purpose of controlling the operation of the unit, as will now be explained.

Thus, with specific reference to FIGURE 2 of the drawings, assuming that the initial position of the unit is at one end of the furnace F, a main switch 20 is manually operated to connect the rails 12 to the main power supply 21 to initiate the overall operation of the unit. Master control circuit 22 thus receives power through the turntable 6 for initiating the movement of the unit along the furnace F to perform the crust breaking, charging and shifting operations in proper sequence as desired. It should be pointed out that the control circuit 22 itself does not per se form any part of the present invention and may be any one of a number of conventional devices, such as for example, a conventional rotary wiper selector that is stepped around in a circle to actuate a plurality of individual switches to bring about successive operations in timed sequence; it being understood that other electronic switching circuits and computers may be employed if desired.

The circuit 22 is arranged to first initiate the operation of the crust breaker 10 as soon as the main switch 20 is closed. The reversible drive motor 3 is connected to the control circuit 22 through a conventional start delay relay 25 so that it can be started next with a certain time delay selected to correspond to the time required for the crust breaking tool 10a to initially break through the crust. Similarly, the silo valve 13 for operating the proper tube 14, 14a that follows directly behind the tool 10a is operated through a second start delay relay 26 so that the charging operation takes place only after the unit has

moved a short distance along the furnace F and the crust has been broken. If desired, as an additional safety feature, the relay 26 may be provided with an interlock switch 27 positioned so as to directly sense the presence of an opening in the crust before allowing the completion of the circuit to open the valve 13.

After the time of the delays 25, 26 has elapsed, the unit advances along the furnace F with the crust breaker 10 breaking a lane in the crust and the charge being fed from the silo 4 until the unit reaches the end of the furnace F. At this point, the appropriate switch 18, 19 strikes its corresponding arm 18a, 19a whereby the control circuit terminates the operation of the motor 3 and the crust breaker 10 and operates the valve 13 to terminate the flow of oxide from the tube 14, 14a.

In order to be able to move the unit over to the next furnace row when the operation on the furnace F is complete, the master control circuit 22 next operates a hydraulic valve 30 which is connected to actuate the hydraulic cylinder 16 by introduction of fluid from hydraulic power source 31 whereby the wheels 15 are lowered and the entire unit is raised. At the same time, the valve 30 may be connected to actuate the cylinder 9 whereby the arm 5 (FIGURE 1) is automatically lowered so that the current collectors 11 are released from the power rails 12. One of the wheels 15 is driven during the transverse run by a separate motor 32 from a separate power source 33 which may take the form of a movable conductor provided with a plug and cooperating with an electrical outlet in the wall W.

If the current rails 12 of the next furnace row are positioned on the opposite wall from the illustrated wall W, the arm 5 may be turned 180° in the horizontal plane by actuation of the motor 8 during this transverse movement on the wheels 15.

In this disclosure, there is shown and described only the preferred embodiment of the invention, but, as aforementioned, it is to be understood that the invention is capable of various changes or modifications within the scope of the inventive concept as expressed by the accompanying claims. Obviously, the unit of the invention may, for example, be provided with security means, instruments and further equipment which might be desired due to local considerations. In any case, it will be realized that the travelling gantry unit of the present invention affords an extremely efficient and simplified means by which the charging operation may be automatically performed in a continuous fashion along either a single furnace F or along a plurality of furnaces F, F' in succession, if desired.

We claim:

1. An apparatus for operating an elongated aluminum electrolysis furnace positioned along a floor having a body of molten aluminum upon which crust breaking and oxide charging operations are to be performed, comprising a gantry framework for spanning the furnaces, said framework being movable longitudinally along said furnace, a silo for charging material mounted on said framework along a leg of said framework adjacent the side of said furnace, said silo being provided with outlet means having a discharge opening adjacent the crust formed on the aluminum in said furnace, a valve for controlling the flow of charging material from said outlet means into said furnace, a crust breaking device on said framework in juxtaposition with said silo for operation on the crust formed on said body adjacent said outlet opening, electric switch means on said framework, first and second stationary stop means provided at opposite end of said furnace for operating said switch means, drive means on said framework for engagement with said floor to move the same along said furnace, and control means for operating said drive means, said crust breaking device and said valve in proper sequence, said switch means being connected to said control means to terminate the operation of said drive means, said crust breaking device and said

valve at the ends of said furnace whereby said operations are performed along the full length of the furnace.

2. An apparatus as claimed in claim 1, wherein said gantry framework is provided with auxiliary means for raising said drive means free of said floor and for causing shifting movement of said apparatus transversely of said furnace to allow placement of the same in position spaced transversely from said furnace.

3. An apparatus as claimed in claim 1, wherein is further provided power rails extending along at least one side of said furnace, said gantry framework being provided with a horizontal boom for supplying power to said apparatus from said power rails, a turntable for mounting said boom for adjustable movement about a vertical axis, and motor means for operating said turntable, whereby said boom is adapted for cooperation with said power rails extending longitudinally of the furnaces on either side thereof.

4. An apparatus as claimed in claim 1, wherein is further provided horizontal pivot means on said boom, and power means for operating the free end of said boom whereby said boom may be lowered away from said power rails.

5. An apparatus as claimed in claim 2 wherein said auxiliary means comprises a plurality of wheels on said framework, said wheels being mounted on pivotal arms having a horizontal pivot axis, power means connected to said arms for movement of said wheels toward and away from said floor.
